A. POLLAK

FOUNTAIN PEN

Filed Sept. 13, 1923

By his Attorney

ABRAHAM POLLAK:

Charles C. Gill.

UNITED STATES PATENT OFFICE.

ABRAHAM POLLAK, OF NEW YORK, N. Y., ASSIGNOR TO SAMUEL KANNER, OF NEW YORK, N. Y.

FOUNTAIN PEN.

Application filed September 13, 1923. Serial No. 662,377.

To all whom it may concern:

Be it known that I, ABRAHAM POLLAK, a citizen of the United States, and a resident of New York city, in the county of New York and State of New York, have invented certain new and useful Improvements in Fountain Pens, of which the following is a specification.

The invention relates to improvements in fountain pens of the self-filling type, and the invention resides in the novel features of construction and combinations and arrangements of parts hereinafter described, and particularly pointed out in the claims.

One object of the invention is the production of a fountain pen whose main barrel portions may be conveniently formed from sheet metal and readily assembled. A further object of the invention is to provide novel and efficient means for securing the operating or filling-lever in position without the use of rivets or the like, and a further purpose of the invention is to provide a novel leaf spring for engaging and collapsing the ink-holding bag and exerting uniform pressure against a considerable length of same and also novel means for holding said spring and applying the same to position.

The invention and satisfactory means for carrying the same into effect will be fully understood from the detailed description hereinafter presented, reference being had to the accompanying drawings, in which:

Fig. 1 is a central longitudinal section through a fountain-pen embodying my invention, the ink-bag being shown in expanded condition and partly broken away;

Fig. 2 is a like view of the same, showing the bag as having been collapsed by the means provided for that purpose;

Fig. 3 is a longitudinal section, partly broken away, through the barrel portions of the pen and illustrates the inner barrel portion carrying the filling-spring as inserted part-way into the outer end of the outer barrel portion and to a position to receive in depressed bearings or seats formed thereon, the trunnions carried by the operating or filling-lever and which trunnions are at that point inserted downwardly through a cross-slot formed in the outer barrel portion and engage said bearings or seats, preparatory to said trunnions on the further inward movement of said inner barrel mem-

ber being carried, with said bearings, below solid portions of the outer barrel or to their final operative position shown in Figs. 1 and 2;

Fig. 4 is a plan view of that portion of the outer barrel shown in Fig. 3, this figure showing the longitudinal slot for accommodating the operating or filling-lever and the cross-slot for permitting the trunnions on said lever to be inserted downwardly to the bearings or seats provided for them on the inner barrel member when said member is partly within the outer barrel or in the position shown in Fig. 3;

Fig. 5 is a plan view of that portion of the inner barrel-member shown in Fig. 5, with the spring connected therewith, this figure showing the two depressed seats or bearings for the trunnions on the operating lever;

Fig. 6 is a cross-section, on a larger scale, taken on the dotted line 6—6 of Fig. 3, showing the trunnions on the operating lever as having been lowered to reach the bearings or seats on the inner barrel member when said member is in its partly inserted position illustrated in Fig. 3;

Fig. 7 is a cross-section, on an enlarged scale, taken on the dotted line 7—7 of Fig. 2, the inner barrel member then having been pushed home and having carried the trunnions and their bearings or seats inwardly below solid portions of the outer barrel;

Fig. 8 is a cross-section, on a larger scale, taken on the dotted line 8—8 of Fig. 2;

Fig. 9 is a detached perspective view of the filling-spring, and

Fig. 10 is a cross-section through the cap portion of the pen taken on the dotted line 10—10 of Fig. 1.

In the drawings, 15 designates the main outer barrel of the pen, this barrel being preferably a sheet metal tube formed in one side of its rear portion with a longitudinal slot 16 and having within its forward end a suitable plug 17 to receive a pen 18 and the forward end of the usual ink-bag 19, which extends rearwardly through the barrel to the requisite distance, as shown, and is entirely closed except at its forward end. The slot 16 is formed at a suitable location between its ends with oppositely disposed transverse recesses 20 which constitute a cross-slot.

Within the rear end of the barrel 15 is

inserted an auxiliary barrel member 21 which is open at its forward end and closed at its outer or rear end by a head 22, into a groove around which, the outer edges of the member 21 are flanged as means for securing said head and member together. When the barrel member 21 is pushed home into the outer end of the barrel 15, or to the position shown in Figs. 1 and 2, an annular enlargement of the outer end of the head 22 brings up against the outer end of the barrel 15 as a stop to arrest the inward movement of the member 21, the annular edges of said enlargement then lying flush with the outer 15 surface of the barrel 15.

The barrel member 21 has in its upper side a long slot or opening 23, and conveniently near its forward or inner end said member 21 is formed at opposite sides of 20 said slot with transverse depressions 24 which form bearings or seats for the trunnions 25 extending transversely from opposite sides of the operating lever 26. When the barrel member 21 is slid into the barrel 25 15, the slot or opening 23 moves along below the slot 16 in said barrel 15 and the bearing-recesses 24 pass below the recesses or cross-slot 20 and thence move forwardly below solid portions of the barrel 15 at opposite 30 sides of the forward end of the slot 16, as hereinafter explained and as is shown in Figs. 1, 2 and 7.

The presser bar, numbered 27, at the upper side of the ink-bag 19, is an elongated 35 bar so as to engage a very considerable length of the bag 19, as shown, and this bar is free at its outer or rear end and at its inner end is secured by a rivet to the leaf spring 28, which is above and extends rearwardly beyond the bar 27, the rear end of the spring 28 being curved downwardly and secured at its lower member 29 below and by means of a loop 30 slit and pressed up from the rear lower portion of the inner 40 barrel member 21, as shown in Figs. 1, 2, 3 and 8. The loop 30, when pressed upwardly from the body of the barrel member 21, receives below it the member 29 of the spring 28, and then when the loop 30 is 45 pressed downwardly against said end of the spring, the spring becomes securely clipped within the barrel member 21. The spring 28 is formed intermediate its ends with a longitudinal slot 31, clearly shown in Fig. 9, and this slot 31, when the parts are assembled, lies partly below and partly in advance of the forward end of the slot 16 formed in the outer barrel 15, and said slot 50 31 also lies below the forward end of the slot 23 in the inner barrel member 21, as shown in Fig. 5. In the normal condition of the bar 27 and spring 28, the body of said spring 28 is straight and the bar 27 lies close up against the lower surface of the same, as 55 shown in Fig. 9; this condition is illustrated

in Fig. 1 wherein it may be seen that the presence of the spring 28 and bar 27 does not interfere with the insertion of an ink bag 19 of considerable length within the outer barrel 15 and inner barrel member 21. 70 The spring 28 is flexed to normally lie at the upper side of the inner barrel member 21, and remains in that position until turned downwardly by pressure exerted against the bar 27 by means of the operating lever 26 75 to depress said bar against the upper side of the bag 19, the action of said lever being primarily against the bar 27 and said bar acting to draw the forward end of the spring 28 downwardly. 80

The lever 26 is a small metallic oscillatory bar-lever having an outer exposed portion adapted to lie along the upper side of the barrel 15 and to be turned upwardly therefrom by the user of the pen, and said lever 26 has a lower portion 32 to engage the bar 27, as shown in Figs. 2 and 3, and is provided with transverse trunnions 25 adapted to the bearings or seats 24 formed on the inner barrel member 21, as hereinbefore explained. 85

The lower member 32 of the lever 26 when said lever is in its normal inoperative position shown in Fig. 1, lies within the slot 31 of the spring 28, and its length is then against the bar 27. When the exposed portion of the lever 26 is turned upwardly from the barrel 15, the lower member 32 thereof is turned downwardly against the bar 27 and depresses said bar against the ink-bag 19, as shown in Fig. 2, for squeezing the air therefrom, so that when the lever 26 is restored to its former inoperative position, a suction may be created within the bag which will draw in ink, according to well-known methods. The spring 28 carries the bar 27, which is depressed by the lever 26 and lifted by the spring 28 with each release of said lever from the bar. 95

The construction hereinbefore described permits of a novel assembly of the lever 26 with the other portions of the pen, and in respect to this part of the invention, I first introduce the inner barrel member 21 into the barrel 15 to the position shown in Fig. 3, said inner barrel member in that position having its bearings or seats 24 directly below the recesses or cross-slot 20 in the barrel 15. When the parts are in this relation I introduce the lever 26 downwardly through the slot 16 of the barrel 15 and the slot 31 of the spring 28 and against the bar 27 and I cause the trunnions 25 to engage the bearings or seats 24 above referred to, and thereupon and while holding the lever in this position, which is shown in Fig. 3, I push the inner barrel member 21 forwardly to its final position within the barrel 15, this action carrying the seats or bearings 24 and the trunnions 25 forwardly from below the 100

110

115

120

125

130

recesses or cross-slot 20 to below the solid portions of the barrel 15 at the forward end of the slot 16, said trunnions 25 then being pivotally held between the bearings or seats 5 24 and the adjacent surface above them of the barrel 15, as shown in Figs. 1, 2 and 7. In this manner of assembly it will be seen that the parts may be very quickly brought together and the lever 26 secured in position 10 without the use of rivets or like means. After the lever 26 has been properly secured, said lever will be turned downwardly against the outer surface of the barrel 15 and into, as far as may be, the slot 16 therein, as shown in Fig. 1. When the lever 26 is turned downwardly against the barrel 15, the spring 28 will flex upwardly and carry the presser bar 27 upwardly to the position shown in Fig. 1, in which position the spring 15 and bar allow abundant space for the ink-bag 19.

The plug 17 has an inner threaded section 33 and from this section 33 extends a nipple 34 which receives the forward end of the 25 rubber bag 19, as shown in Fig. 2. The forward end of the barrel 15 has a thread 35 formed thereon and this thread engages the threaded section of the plug 17, the barrel 15 thus being connected with the plug 17 by 30 screw threads.

The forward portion of the pen structure is adapted to receive a protecting cap 36, which is formed from a sheet metal tube and is open at one end to slip upon the pen 35 structure and closed at its outer end by a metal disk 37. Within the cap 36 is a hard rubber sleeve 38 which has a friction fit within the cap 36 and is open at both ends and near its outer end is annularly recessed, 40 as at 39, to stand clear of the inner walls of the cap 36. Adjacent to its inner end the sleeve 38 is annularly recessed and threaded to receive the adjacent threaded end of a metal sleeve 40, which is inserted into the body of the cap 36 with the sleeve 38, the sleeve 40 preferably being screwed upon the sleeve 38 so that both sleeves may, as a 45 unitary structure, be inserted into the body of the cap 36, wherein said parts are stationary. The outer end of the sleeve 40 is threaded, as at 41, and into this thread the thread 35 on the barrel 15 is screwed when it is desired to secure the cap 36 in position over the pen point 18. The thread 35 on 50 the barrel 15 thus serves to secure the plug 17 in place and also as means for engaging the thread 41 on the sleeve 40 and thereby securing the cap 36 detachably over the forward portion of the pen structure. When 55 the forward end of the barrel 15 is screwed into the sleeve 40, the forward annular edge of the plug 17 abuts against the rubber sleeve 38, as shown in Fig. 1, and thereby a fluid-tight joint is formed between said plug 60 and sleeve.

I provide the cap 36 with a spring clip 42 for permitting the fountain pen to be secured within the vest pocket, as usual. The clip 42 consists of a spring tongue of known character extending rearwardly along the 70 cap 36 from a plate 43 which defines a portion of a circle and lies within the annular recess 39 formed in the sleeve 38, as shown in Figs. 9 and 10. The plate 43 closely embraces the end of the sleeve 38, and the recess 39 in said sleeve is provided to receive the plate 43, which plate is confined at the inner side of the cap 36 and is held in place without riveting or the like. The outer end of the cap 36 is recessed in its edge portion, as at 44, and this is for the purpose of admitting the sleeve 43 to the recess 39 around the sleeve 38 and to permit the tongue portion of the clip to extend laterally from the cap 36 and along the side of said cap. The 80 outer end of the cap 36 is spun over upon the disk 37, as shown in Fig. 1, and prior to the spinning or flanging over of the edges of the cap 36 upon the disk 37 I introduce the sleeves 38, 40 and the plate 43 of the 85 clip 42 into the cap 36, and then close the outer end of the cap by inserting the disk 37 in position and spinning over the edge portions of the end of the cap upon said disk, the recess 44 in the end of the cap permitting me to follow this practice.

What I claim as my invention and desire to secure by Letters Patent, is:

1. A fountain pen comprising an exterior barrel or casing member having at its forward end a plug and pen and containing a collapsible bag for holding ink and in communication with the chamber of said plug for feeding the pen, an elongated bar engaging the exterior upper side of said bag, an elongated spring to which the forward end of said bar is secured and which has a downward return bend at its rear end, an inner barrel member insertible into said exterior barrel member from the rear end thereof and to which the end of said bend of the spring is secured, said inner barrel member carrying said spring and bar and said bend flexing the body of the spring upwardly to position said bar horizontally with relation to said bag, and a pivoted lever on the casing having an outer member for manual operation and an inner member to be turned downwardly against said bar for depressing the same against said bag in opposition to the force of said spring, said inner barrel member having at its lower side an integral upwardly pressed loop to receive and serve as a clip for securing the end of said spring bend and at its upper side a longitudinal slot through which the said lever operates.

2. A fountain pen comprising an exterior barrel or casing member having at its forward end a plug and pen and containing

a collapsible bag for holding ink and in communication with the chamber of said plug for feeding the pen, an elongated bar engaging the exterior upper side of said bag, 5
an elongated spring to which the forward end of said bar is secured and which has a downward return bend at its rear end, an inner barrel member insertible into said exterior barrel member and to which the end 10 of said bend of the spring is secured, said inner barrel member carrying said spring and bar and said bend flexing the body of the spring upwardly to position said bar horizontally with relation to said bag, and a 15 pivoted lever having an outer member for manual operation and an inner member to be turned downwardly against said bar for depressing the same against said bag in opposition to the force of said spring, said 20 lever having laterally extending trunnions, and said inner barrel member being longitudinally slotted and having bearings for said trunnions below solid portions of the outer barrel member, said outer barrel member being longitudinally slotted to admit 25 the said lever and cross slotted to permit said trunnions to be lowered to said bearings when the inner barrel member is arrested during its insertion into the outer barrel 30 member with its longitudinal slot below the longitudinal slot of said outer barrel member and its bearings below the cross-slot of said outer barrel member.

3. A fountain pen of self-filling type containing an ink-bag and presser-bar therefor, comprising an outer barrel member having a longitudinal slot and a cross-slot transverse of said longitudinal slot, an inner member insertible endwise into said outer member and having a longitudinal slot to pass below the longitudinal slot of said outer member and also bearings at opposite sides of its slot to be arrested below said cross-slot during the insertion of said inner member and then moved forwardly beyond the longitudinal slot of said outer member and below solid portions of said outer member, and a pivoted operating lever for said bar having an outer member for manual operation, an inner member to depress said bar and trunnions adapted to be lowered through said cross slot and seated on said bearings when the latter are arrested below

said cross-slot and then to be carried on the bearings below solid portions of the outer member on the further movement of said inner member to its final position. 55

4. A fountain pen of self-filling type containing an ink-bag and presser-bar therefor, comprising an outer barrel member having a cross-slot, an inner member insertible endwise into said outer member and having a longitudinal slot and bearings at opposite sides thereof to be arrested below said cross-slot during the insertion of said inner member into said outer member and then moved forwardly below solid portions of said outer member, and a pivoted operating lever for said bar having an outer member for manual operation, an inner member to depress said bar and trunnions adapted to be lowered through said cross-slot and seated on said bearings when the latter are arrested below said cross slot and then to be carried on the bearings below solid portions of the outer member on the further movement of said inner member to its final position. 60 65 70 75

5. A fountain pen of self-filling type containing an ink-bag and presser-bar therefor, comprising an outer barrel member having a cross slot, an inner member insertible endwise into said outer member and having a longitudinal slot and bearings at opposite sides thereof to be arrested below said cross slot during the insertion of said inner member into said outer member and then moved forwardly below solid portions of said outer member, and a pivoted operating lever for said bar having an outer member for manual operation, an inner member to depress said bar and trunnions adapted to be lowered through said cross slot and seated on said bearings when the latter are arrested below said cross-slot and then to be carried on the bearings below solid portions of the outer member on the further movement of said inner member to its final position, said inner member being tubular and carrying said bar and having on its outer end a head whose forward annular edges engage the rear end of said outer barrel member and close the same. 80 85 90 95 100

Signed at New York city, in the county of New York and State of New York, this 4th day of September, A. D., 1923.

ABRAHAM POLLAK.
